UNITED STATES PATENT OFFICE

144,670

DESIGN FOR A COMBINED CRIB AND UTILITY CABINET

Raymond L. Adolf, Galesburg, Ill., assignor to Raymond L. Adolf and Victor E. Groppe, a partnership doing business as Wee Folks Furniture Company, St. Louis, Mo.

Application October 15, 1945, Serial No. 122,837

Term of patent 14 years

(Cl. D5—5)

To all whom it may concern:

Be it known that I, Raymond L. Adolf, a citizen of the United States and a resident of Galesburg, in the county of Knox and State of Illinois, have invented a new, original, and ornamental Design for a Combined Crib and Utility Cabinet, of which the following is a specification, reference being had to the accompanying drawing, forming part thereof.

Fig. 1 is a front perspective view of a combined

crib and utility cabinet, showing my new design.

Fig. 2 is a similar perspective view looking at the end opposite from that shown in Fig. 1 and with the drawers opened; and

Fig. 3 is a rear elevational view.

I claim:

The ornamental design for a combined crib and utility cabinet, substantially as shown.

RAYMOND L. ADOLF.
